UNITED STATES PATENT OFFICE.

WALTER J. THOMAS, OF MODESTO, CALIFORNIA, ASSIGNOR OF ONE-HALF TO LOREN W. DAVIS, OF MODESTO, CALIFORNIA.

AUTO JACK.

1,413,143.

Specification of Letters Patent. Patented Apr. 18, 1922.

Application filed March 3, 1920. Serial No. 362,931.

To all whom it may concern:

Be it known that I, WALTER J. THOMAS, a citizen of the United States, residing at Modesto, in the county of Stanislaus and State of California, have invented a new and useful Improvement in Auto Jacks, of which the following is a specification.

This invention relates to an auto jack and especially to a jack which is sufficiently large to receive an entire machine and capable of lifting either end thereof.

In some private, and in most public garages it is customary to employ pits or the like over which the machines are run when they are to be inspected, repaired or otherwise. Most garages are only equipped with one pit and if it happens that the machine to be repaired is partly taken down, it is obvious that other machines requiring only minor attention will have to wait until the machine occupying the pit is completed and removed. Other garages again employ low wooden racks on which the mechanics lie and work themselves under the automobiles. This method and also the pit method is exceedingly objectionable for the reason that the mechanics are in a cramped and difficult position and generally without sufficient light.

One of the objects of the present invention is to provide a simple substantial frame or jack adapted for use in garages and like places which may be moved about to any convenient position and which is so constructed that the vehicle can be readily run upon the jack and then become tilted endwise to a suitable height so that ready access to the lower or underneath portion of the vehicle may be had.

Another object of the invention is to provide a screw actuated lifting mechanism whereby comparatively heavy vehicles may be readily and quickly lifted by a single operator, and to provide means for securing the vehicle both against lateral and endwise movement on the jack frame when in tilted position.

Further objects will hereinafter appear.

The invention consists of the parts and the construction, combination and arrangement of parts as hereinafter more fully de-

scribed and claimed, having reference to the accompanying drawings, in which—

Fig. 1 is a side elevation of the jack showing an automobile in position thereon. 55

Fig. 2 is a detail view of the crank lever and the reversible pawls carried thereby.

Fig. 3 is a plan view of the jack.

Fig. 4 is a cross section on line 4—4, 60 Fig. 3.

Referring to the drawings in detail, A indicates a base frame and B a tilting frame. The tilting frame is pivotally attached to the base frame A as at 2, and may therefore be elevated or tilted to assume the dotted line position indicated at C. The base frame is constructed of any suitable material, either wood or metal, while the tilting frame is constructed of a pair of channel iron track members 3, 70 which are secured and held in spaced relation by means of cross bars 4. The base frame is provided with journal members 5 at one end and similarly the tilting frame B. A shaft 6 extending therethrough forms 75 the pivotal connection about which the frame is tilted. The spacing between the track members is such that they are adapted to receive the wheels of an auto as shown and the length of the track members and 80 the base frame A is of course varied to suit autos of different sizes and length, for instance a standard form of jack may be employed for smaller machines and another size for machines of a larger type. The 85 forward ends of the track members are bent downwardly as at 7 to permit the front and rear wheels of an auto to easily enter the track members 3, and the rear ends of the track members are bent upwardly as at 8 90 to form a stop which will secure the auto against endwise movement when in tilted position.

For the purpose of tilting the frame B a screw jack mechanism generally indicated 95 at D has been provided. This mechanism consists of a pair of screw rods 9, one positioned on each side of the frame. These screw rods are pivotally mounted as at 10 in bracket members and may therefore assume an angular position as the frame B is lifted or tilted. The rods 9 are supported

by the base frame A, while a cross shaft 11 is supported and journalled in the tilting frame B. This shaft has a worm gear 12 secured at each end which intermeshes with 5 a pair of worm wheels 14. These wheels are internally threaded to fit the screw rods 9 and therefore serve the function of lifting nuts as will hereinafter be described. The gears 14 are journalled between the 10 lugs 15 carried by the tilting frame, said lugs being disposed above and under each gear or nut to prevent endwise movement of the same with relation to the tilting frame.

15 Turnably mounted on one end of the shaft 11 is a hand crank 16, and secured on the shaft, on each side of said crank, are ratchet gears 17. The teeth on the ratchet gears are reversed with relation to each other and two 20 pawls 18 are therefore carried by the crank arm to permit engagement with either ratchet gear. For instance with an auto in position on the frame when it assumes a horizontal position, it is only necessary to 25 throw one of the pawls into engagement with one of the ratchets 17. The crank arm is then oscillated by the operator until the tilting frame assumes a position where a complete tilting movement may be imparted 30 to the crank arm and the shaft. The turning movement transmitted to the shaft 11 is in turn transmitted through the worms 12 to the gears 14 and as these are internally threaded and engage the threads of the screw 35 rods 9, it is obvious that they will gradually climb the rods and consequently lift the tilting frame to any position desired, the screw jack being locked in any position due to the fact that reverse movement of the worm 40 gear transmission employed cannot take place except by power transmitted thereto through the crank arm. Therefore when it is desired to lower the tilting frame it is only necessary to disengage the pawl last 45 employed and to engage the opposite pawl and then to turn the shaft 11 in the opposite direction. This of course reverses the turning movement of the gears 14 and thereby permits the same to descend on the screw 50 rods and thereby lower the frame. The pawls 18 may be constructed in any suitable manner but preferably as here shown as the slotted extension 19 and the spring 20 employed, permits the pawl to be held in engagement by spring tension or to be held out of engagement with spring tension. This is desirable as it will prevent one pawl 55 from interfering with the other when raising or lowering the tilting frame.

60 A jack or tilting frame constructed as here shown is exceedingly simple in construction and as it lies flat, it is obvious that it can be readily pulled about a garage and placed wherever convenient, for instance near a 65 window where plenty of light may be had

when working on a machine. Several jacks of the character here shown may be employed by one garage and as they may be moved about to suit varying conditions, it is obvious that one or more machines may be worked upon 70 at one time, this being of great advantage when compared with the pit as most garages seldom employ more than one pit and can therefore only work on one machine at a time. The mechanic is furthermore cramped 75 when working under such conditions and lighting conditions are seldom favorable. The present jack permits tilting of the machine to almost any angle desired, thereby permitting the mechanics to work without 80 being cramped and where sufficient light may be had at all times.

The jack shown is not only useful in public garages, but also for private use as it can at all times be handled by one operator, 85 whether raising the machine or lowering the same. It is also possible to work on either end of the machine as the front wheels are brought into engagement with the stop 8 when the rear end is to be worked on, and 90 conversely the machine is backed upon the frame when it is desired to work on the engine or the front end of the machine. The jack is not only useful for repairing, inspection or otherwise, but may be employed to 95 great advantage when painting.

While a more or less specific structure is shown, I wish it understood that various changes in design and proportion may be resorted to within the scope of the appended 100 claims, similarly that the materials and finish of the several parts employed may be such as the experience and judgment of the manufacturer may dictate or varying conditions may demand.

Having thus described my invention, what I claim and desire to secure by Letters Patent is—

1. In a device of the character described a base frame, a tilting frame, a pair of track members on the tilting frame for the reception of an automobile, a pivotal connection between the base frame and the tilting frame, a pair of screw rods pivotally mounted one on each side of the base frame, a pair 110 of brackets on each side of the tilting frame, a nut on each screw rod positioned between said brackets, a shaft extending crosswise of the tilting frame and journalled therein, a worm gear exterior of each nut, a pair of worm gears on the shaft one engageable 115 with each first named worm, and means for imparting a turning movement to the shaft in either direction to turn the connected worms and nuts upon the screw rods in either direction.

2. In a device of the character described a base frame, a tilting frame, a pair of track members on the tilting frame for the reception of an automobile, a pivotal connection 120

between the base frame and the tilting frame, a pair of screw rods pivotally mounted one on each side of the base frame, a pair of brackets on each side of the tilting frame, a 5 nut on each screw rod positioned between said brackets, a shaft extending crosswise of the tilting frame and journaled therein, a worm gear exterior of each nut, a pair of worm gears on the shaft one engageable 10 with each first named gear, a crank arm turnably mounted on one end of the shaft, a pair of reverse ratchet gears secured on the

shaft one on each side of the crank arm, a pair of pawls carried by the crank arm one for each ratchet, and means for holding 15 either pawl in or out of engagement with its respective ratchet.

In testimony whereof I have hereunto set my hand in the presence of two subscribing witnesses:

WALTER J. THOMAS.
